UNITED STATES PATENT OFFICE.

LUCIUS E. WHITON, OF NEW LONDON, CONNECTICUT.

PROTECTION OF SHIPS AGAINST TORPEDOES.

1,369,588.

Specification of Letters Patent. Patented Feb. 22, 1921.

Application filed June 9, 1917. Serial No. 173,693.

To all whom it may concern:

Be it known that I, LUCIUS E. WHITON, a citizen of the United States of America, residing at New London, Connecticut, have 5 invented a new and useful Protection of Ships Against Torpedoes, of which the following is a specification.

My present invention aims primarily to provide a practical and efficient protection 10 against attack by torpedoes which can be readily assembled from material usually at hand and which can be readily placed in operative position.

This is an improvement on the invention 15 of my application #170,847 filed May 25th, 1917.

A further object is to provide means of this character which will not materially impede or retard the movements of a ship or 20 interfere with the handling of the ship.

In brief the invention comprises a protecting wall of inherently buoyant material such as wood, which is floated on edge at the side of the ship and is weighted so as to 25 maintain itself in an upright position. This wall is usually towed by the ship at a distance from the side of the ship. A convenient and practical method of weighting the wall is to use ordinary anchor chain which 30 can be suitably attached to the lower edge portion of the wall.

In the accompanying drawings wherein I have illustrated a practical embodiment of the invention —

35 Figure 1, is a top plan view and

Fig. 2 is a side elevation showing the application of the invention to the protection of a ship.

Fig. 3, is an enlarged broken view of a 40 section of the protecting wall.

Fig. 4, is an edge view of the same illustrating in dotted lines the lateral movements of the upper flexible sections of the wall.

Fig. 5, is a broken side elevation of a 45 slightly modified form of protecting wall.

As appears most clearly in Fig. 2 the wall is preferably made up of a plurality of units or sections 7 arranged in tandem and flexibly connected at their adjoining ends as by 50 means of the connecting loops 8.

These sections are constructed of suitable, available, inherently buoyant material such as wood, flat boards being preferably used for the purpose so as to offer as little resistance as possible to movement through the water and which may be fastened to-

gether in any convenient manner as by nailing or bolting a series of horizontally disposed boards across a series of vertically or diagonally arranged boards.

60

The floating sections are weighted so as to stand upright in the water as by securing angle irons 9 to the lower edges of the sections and suspending anchor chain 10 from said lower edges. A convenient method of 65 suspending the anchor chain is to provide suspending hooks 11 having eyes 12 through which are passed the bolts 13 which secure the angle irons in place, certain of the links of the anchor chain being engaged over these 70 hooks as indicated in Fig. 4. The angle irons, bolts, hooks and anchor chain are standard articles, readily obtainable and it will be evident that the wall sections may be made up in suitable sizes of any lumber 75 which is available in a given locality so that it is possible to build the structure whenever and wherever the case may require.

The wall or stockade is usually arranged in a series of overlapping trains as indicated 80 at 7^a and 7^b in Fig. 1, disposed at some distance from the side of the ship and with a space 14 between the two series of floats to provide a gap or space for the passage of the surface wave thrown by the bow of the ship. 85

In the illustration these two wall sections are towed by lines 15, 16 carried by spars 17 outstanding from the bow of the ship, these spars being suitably braced as by means of outrigging 18. This towing arrangement 90 may be duplicated at the stern so as to steady the protecting walls and cause them to follow the ship's movements when the ship is traveling astern.

In order that the barricade can accommodate itself more or less to the cross currents of the surface water, the upper or surface water portions of the protection may be made flexible or yielding in character, as by making them in sections 19, hinged at 20 100 to the lower or main body portion of the barrier. These flexible upper portions may be flexibly joined together as by means of a suitable connection such as the rope 21, shown woven in and out between the adjoining sections.

If the upper flexible portions prove to be unnecessary under certain conditions, the barrier may be made in solid panels such as indicated at 22 in Fig. 5, which shows the 110 boards of a panel united at the bottom by the angle irons 9 and at the top, by a cross

batten 23. The upper edge of the barrier may be notched as indicated at 24 to allow free passage of the surface water.

I claim:—

5 1. Means for protecting a ship from torpedo attack comprising an independently floating wall of inherently buoyant material floated on edge at the side of a ship and weighted in its lower portions to cause said 10 buoyant wall to stand upright in the water and through the zone of attack by torpedoes and means for towing said buoyant wall at the side of a ship.

15 2. Means for protecting a ship from torpedo attack comprising an independently floating wall of inherently buoyant material floated on edge at the side of a ship and weighted in its lower portions to cause said 20 buoyant wall to stand upright in the water and through the zone of attack by torpedoes, said wall having flexible upper portions yieldable to the movement of the surface water and means for towing said floating wall at the side of a ship.

25 3. Means for protecting a ship from tor-

pedo attack comprising, an independently floating wall made up of flexibly united sections of inherently buoyant material floated on edge at the side of a ship and weighted to stand upright in the water and means 30 for towing said upright wall at the side of a ship.

4. Means for protecting ships from attack by torpedoes, comprising an independently floating buoyant wall of wood, weights 35 attached to the lower portions of said wooden wall for floating the same upright in the water and means for towing said wall.

5. Means for protecting ships from attack by torpedoes, comprising an independently floating wall of inherently buoyant material floated on edge at the side of a ship, weighted at its lower portion to cause the same to stand upright in the water and towing means attached to the lower portion 40 of said wall, the upper portion of said wall having flexible sections yieldable laterally 45 to accommodate themselves to movements of the surface water.

LUCIUS E. WHITON.
